TIME DELAY DEVICE

Thomas P. Farkas, Bloomfield, Conn., assignor to United Aircraft Corporation, East Hartford, Conn., a corporation of Delaware
Original application Sept. 21, 1956, Ser. No. 611,337. Divided and this application Aug. 25, 1960, Ser. No. 51,954

3 Claims. (Cl. 91—443)

This invention relates to a fluid servo system and more particularly to a servomotor which is capable of translating at various speeds. This constitutes a divisional application taken from my copending application No. 611,337, filed September 21, 1956, and entitled "Fuel Control," now issued as United States Patent No. 2,968,347.

It is an object of this invention to provide a means for regulating the speed of a servomotor so that it will move at a predetermined rate in one direction and at a selected increased rate in the opposite direction.

It still is a further object of this invention to provide an adjustment for varying the rate in which the servo piston will translate in one of its directions.

It is still a further object of this invention to provide a time delay device which is characterized as being relatively simple in design and construction wherein a single valve functions to control the rate of movement of a servomotor in either direction of its movement.

These and other objects of this invention will become readily apparent from the following detailed description of the drawing:

A detailed description of a fuel control may be had by referring to the above-referred-to Patent No. 2,968,347. But suffice it to say, the fuel is metered by throttle valve 104 and delivered to the engine through passage 50. Fuel is delivered to the metering throttle valve through passages 42 and 102 which are connected to a source of high pressure fuel (not shown). The throttle valve has a pair of cooperating ports which are in rotational and rectilinear relationship with each other. The longitudinal motion is imparted by virtue of piston 182 which is responsive to an engine operating variable sensed by bellows 183. The engine operating variable, such as the pressure of the air discharging from the compressor of the engine, is transmitted into cavity 185 through line 62. This pressure acts on the bellows which in turn transmits a proportional movement to lever 190. This movement in turn varies the orifice 196 which varies the pressure in line 64 downstream of orifice 198. Thus, the pressure established between the variable orifice 196 and the fixed orifice 198 is proportional to the movement of bellows 183 which pressure is also transmitted to chamber 264 by line 262. Thus, the translation of the port attached to piston 182 is proportional to the engine operating variable.

Rotational movement is imparted to the throttle valve 104 in response to the control shaft 228 and cam 226. The control shaft may be connected to the pilot lever in the cockpit of the aircraft (not shown). Movement of the cam 226 controls the movement of pilot valve 224 which in turn governs the application of fluid into chamber 264 which causes translation of the servo piston 222. This translation is converted into rotary movement by virtue of the linkage 212 which is connected to the throttle valve 104. Pressurized servo fluid is directed through line 242 through the pilot valve 224 where it is metered and then directed to chamber 264 via passages 250 and 260 and passes through the time delay mechanism as will be more fully described herein below.

The pressure drop across throttle valve 104 is held

2

at a constant value by virtue of the pressure regulating valve 106. The pressure of the fluid just upstream and downstream of throttle valve 104 are applied on either side of valve 106 and a spring 107 urges the valve closed. The pressure upstream of throttle valve 104 is directed to the valve 106 through passages 102 and 103 and the pressure downstream is directed to the opposing side via passages 50 and 110. When the pressure drop exceeds a value as determined by the size of spring 107, the valve will open and conduct fluid upstream of the throttle valve to drain. In this manner, the pressure drop is maintained at a constant value.

The single drawing generally shows a servo system comprised of a pilot valve 224 and a servomotor 222. 15 The pilot valve essentially functions to direct high pressure fluid issuing from line 242 which is in communication with a source of high pressure servo fluid (not shown) to chamber 264 and communicates chamber 264 to drain by way of annular passage 255 and a restriction formed by the shoulder 257 and the bottom end of the sleeve 253. The pilot valve may be positioned upwardly or downwardly by action of cam 226 and lever 229 which in turn may be connected to a pilot lever. In a fuel control application, for example, which 20 is intended to control the flow of fuel to the combustion section of a turbine type of engine which is more fully disclosed in the above-mentioned patent, the pilot lever through the action of the servo device will position the throttle valve 104 so as to provide the proper metering of fuel. This serves to regulate the quantity of fuel being delivered to the engine. The time delay device is utilized to control the movement of the throttle valve so that the rate of fuel delivered to the engine will take different values depending whether the engine is in an accelerating or decelerating operating regime. The throttle valve may also be controlled by other parameters for further regulation of the fuel. At this point it should be emphasized that any one skilled in the art will realize that the input signal and the output response may be used for supplying power in accordance with an input signal of any variable for obtaining an output response for any other purpose without departing from the scope of this invention.

45 In accordance with this invention, a hydraulic system is interposed between the servo control valve 224 and the servo piston 222 in order to provide for a controlled rate of fuel flow increase and a more rapid rate of fuel flow decrease in response to operation of the pilot's control lever. To this end, a time delay regulator system is provided. This regulator system includes a valve having a piston 232 slidable in a sleeve 234 and urged to the right by a spring 236. A control chamber 240 is provided centrally of the piston 232 which receives fluid under suitable control pressure from the control valve 224.

50 High pressure fluid is directed to the control valve 224 by means of a line 242 to a port 244 at the control valve 224. When the valve stem 246 of the control valve 224 is moved downwardly, high pressure fluid from the port 244 is then conducted to the port 248 whereby it flows into the line 250 then to the chamber 252 of the regulator valve. From chamber 252 the fluid may pass to the port 259, annulus 256, port 258 and then to the chamber 240 within the valve piston 232. Under these conditions fluid 55 under high pressure then flows to the right side of the valve into line 260 past a fixed orifice 262 and then to the chamber 264 on the bottom side of the servo piston 222. It should be noted that the chamber 266 on the top side of the servo piston 222 is continuously exposed to high pressure fluid from a line 268 leading from the line 242.

60 In passing the orifice 262 a pressure drop will be cre-

ated whereby a slightly lower pressure occurs in the chamber 264 as well as the passage 270 which leads around to the left-hand side of the regulator valve piston 232. From the line 270 fluid can then enter a chamber 272 whereby pressure is exerted tending to move the valve piston 232 toward the right. Pressure in the chamber 272 in urging the piston 232 toward the right acts to permit further flow of high pressure fluid to chamber 240 and the line 260. If, for example, a pressure drop across the orifice 262 is 10 p.s.i. with a given supply pressure to the line 250 and the pressure in line 250 is suddenly increased, piston 232 will be urged to the left against the pressure of spring 236, tending to close off port 259 thereby decreasing the pressure in chamber 240 until it reaches a value 10 p.s.i. higher than that of the pressure in chamber 272. Following this, piston 232 will again move sufficiently to the right allowing the flow to continue through the port 259, annulus 256, port 258, chamber 240, line 260 and the chamber 264 at the bottom of the servo piston 222. Stated another way, if, for example, control valve 224 is displaced downward causing supply pressure from line 242 to be directed to line 260 through chamber 252, port 259, port 258, and chamber 240, the pressure drop across orifice 262 will exceed the pressure setting of spring 236 causing piston 232, the opposite ends of which are exposed to the pressures in lines 260 and 270, to move to the left thereby reducing the area of port 259 with the attendant effect of throttling the flow from line 250 to line 260 until the pressure in line 260 exceeds the pressure in line 270 by the amount of the pressure setting of spring 236. With a given value of pressure drop across the orifice 262, it is then possible to establish the rate at which the servo piston 222 will move in an upward or increased fuel flow direction.

When the control valve 224 is moved in an upward direction, the port 248 is connected with drain so that flow in the line 250 is then reversed. This flow reversal begins at the chamber 264 at the bottom of the servo piston 222 so that the fluid attempts to flow downwardly in line 260 past the restriction 262 and into the chamber 240 of the piston 232. With a flow in this direction there is a pressure drop across the restriction 262 whereby the pressure in the line 270 and the chamber 272 at the left-hand side on the piston 232 is higher than the pressure in the chamber 240. This urges the piston 232 to the right against the action of the spring 280 which is located at the right-hand side of the valve piston 232. As the piston 232 moves to the right, it opens port 282 thereby opening chamber 272 to the line 250 and drain. Fluid may now flow rapidly from the chamber 264 at the bottom of the servo piston 222 via the line 270, chamber 272, port 282 and then to the line 250. Thus, the restriction 262 is bypassed and the servo piston 222 can move down rapidly. As the servo piston 222 reaches its downward limit, the pressure in the chamber 264, line 270 and chamber 272 will reduce thereby permitting the piston 232 to move back toward the left to a neutral position.

Considering now the relationship of the time delay servo with the control valve 224 and other system elements, it will be noted that the lever 229 is positioned at one end by the control shaft cam 226 and at its other end 230 by spring 231 which preloads it against servo piston 222. The spring 231 which engages the left end 230 of the lever 229 is incorporated to insure the ability of the system to decrease fuel flow in case of sticking of the servo piston 222. In this event, pilot valve 224 bottoms against its sleeve to act as a fulcrum for lever 229 permitting cam 226 to move the left end 230 of lever 229 downward thus freeing lever 230 from the stuck piston 222 and also causing the throttle valve to move in the decreasing fuel flow direction. As will have been realized from the foregoing, piston 232 which has acting of its opposite sides the fluid pressure upstream and downstream of restriction of 262 serves to maintain the pressure drop across the restriction at a constant value. The force

exerted by spring 236 determines the value of the pressure drop. It is apparent that by selecting the position of screw adjustment 261, the force of the spring can be readily changed in order to effect a change in the value of the pressure drop. Since the pressure drop across 262 is held at a constant value and since there is a fixed restriction, whose area is predetermined, then, of course, when servomotor 222 is being positioned upward, the flow through the restriction 262 will be at a predetermined rate which in turn determines the rate at which servomotor 222 will translate.

In summary then the throttle valve is positioned in accordance with the pilot's power lever position. However, with the time delay servo the throttle valve will be moved to increase fuel flow at a given rate for power lever increase so that in case of a sudden increase fuel flow movement of the power lever, an excessive rate of increase in fuel flow is avoided. On the other hand, when the power lever is moved toward decrease fuel flow, the throttle valve and its servo are moved rapidly toward decrease fuel flow.

Thus if the pilot moved his power lever to the 100% setting, then suddenly reduced the setting to 50% power and then again returned the power lever to the 100% setting rapidly, the fuel flow rate would immediately jump to the 100% setting if downward movement of the throttle servo piston 222 were very slow. For the instant when the power lever called for 50% power, the throttle valve would be set for such a flow through the action of the override spring 231, but when the power lever is pushed up to the 100% setting, the throttle rotating servo piston 222, having already been at a high level from the previous 100% setting and having remained there due to its slow action during the decrease in power lever setting would allow the throttle valve to immediately pass the 100% fuel flow position. The delay feature would thus be ineffective during this type of operation. With rapid downward movement of the throttle valve, servo piston 222, this undesirable feature is eliminated.

What has been shown is a time delay device which is formed by a single valve which serves to control the rate of movement of a servo piston such that the piston will move at a predetermined rate in one direction and at a selected rate in the opposite direction. The rate in which the piston will move in one of its directions can readily be selected by a mechanical adjusting device, and the rate in which the piston will move in the opposite direction will be selectively chosen by the proper positioning of the servo pilot valve.

I claim:

1. In a device having a servomotor, a source of fluid under pressure, a drain, a control valve for connecting one side of said servomotor to pressure or to drain and a time delay device connected between said valve and said servomotor, said time delay device including a restriction for slowing down the flow of fluid to said servomotor, a second valve having a hollow piston therein, said hollow piston being closed at one end and open at the other, a port controlled by said hollow piston normally connecting said restriction through the open end of said hollow piston with said control valve, an expandible chamber, said hollow piston forming one wall of said chamber, a connection between said chamber and said servomotor, the pressure in said chamber when exceeding a predetermined pressure above the pressure within the hollow piston moving said hollow piston in a given direction and a second port in said second valve connecting said motor with drain through said control valve when said hollow piston is so moved.

2. In a device having a servomotor, a source of fluid under pressure, a drain, a control valve for connecting one side of said servomotor to pressure or to drain, a time delay device connected between said valve and said servomotor, said time delay device including a restriction for slowing down the flow of fluid to said servomotor, a

second valve having a hollow piston therein, said hollow piston being closed at one end and open at the other, a port in said hollow piston normally connecting said restriction through the open end of said hollow piston with said control valve, a chamber adjacent the closed end of said hollow piston, a connection between said chamber and said servomotor, the pressure in said chamber exceeding the pressure in said hollow piston during movement of said servomotor in a given direction whereby said hollow piston is moved in a given direction, and a second port opened by movement of said hollow piston in said given direction for leading fluid from said connection to drain.

3. In a device having a servomotor, a source of fluid under pressure, a drain, a control valve for connecting one side of said servomotor to pressure or to drain, a time delay device connected between said valve and said servomotor, said time delay device including a restriction for slowing down the flow of fluid to said servomotor, a second valve having a hollow piston therein, said hollow piston being closed at one end and open at the other, a port in said hollow piston normally connecting said restriction through the open end of said hollow piston with said control valve, a chamber adjacent the closed

5 end of said hollow piston, a connection between said chamber and said servomotor, the pressure in said chamber exceeding the pressure in said hollow piston during movement of said servomotor in a given direction whereby said hollow piston is moved in a given direction, a second port opened by movement of said hollow piston in said given direction, and a connection between said second port and drain bypassing said restriction.
